CLAIM

The ornamental design for a dispenser cap for bottles, as shown and described.

DESCRIPTION

FIG. 1 is a top plan view of a dispenser cap for bottles in accordance with the present design;

FIG. 2 is a front elevation view thereof;

FIG. 3 is a lateral left view thereof;

FIG. 4 is a rear view thereof;

FIG. 5 is a perspective view thereof; and,

FIG. 6 is a rear perspective view thereof.

The bottom and interior of the cap form no part of the claimed design.
